UNITED STATES PATENT OFFICE.

JOHN O'BRIEN, OF ST. LOUIS, MISSOURI.

FLANGING-MACHINE.

SPECIFICATION forming part of Letters Patent No. 341,598, dated May 11, 1886.

Application filed September 26, 1885. Serial No. 178,931. (No model.)

To all whom it may concern:

Be it known that I, JOHN O'BRIEN, of the city of St. Louis, in the State of Missouri, have invented a certain new and useful Improvement in Flanging-Machines, of which the following is a full, clear, and exact description, reference being had to the accompanying drawings, forming part of this specification, and in which—

10 Figure 1 is a side elevation of my improved machine. Fig. 2 is a horizontal section taken on line 2 2, Fig. 1. Fig. 3 is a detail section illustrating the manner of turning over the flange. Fig. 4 is a detail vertical section taken 15 on line 4 4, Fig. 1.

My invention relates to a flanging-machine intended more particularly for forming flanges upon boiler-heads; and my invention consists in features of novelty hereinafter fully described, and pointed out in the claims.

Referring to the drawings, A represents the frame of the machine, having a lower beam, B, and an upper beam, C, and uprights D, the lower beam consisting, preferably, of two 25 plates, as shown in Fig. 2, (forming a long vertical opening between them and the uprights,) which support and upon which slides the mechanism for forming the flange. In the middle of the opening in this beam B is held a box, E, through which passes a short spindle or shaft, F, having upon its lower end a cog-wheel, G, for receiving power from any suitable motor. Upon the upper end of this spindle is a head, G', beneath which and the beam 30 I prefer to place a washer, G''. Supported on the head of the spindle is a disk, J, having connection with the head, as shown in Figs. 1 and 4, and upon this disk rests the plate of metal to be flanged, as shown in Figs. 1 and 4, 40 the plate being held between this disk and a similar disk, K, supported on the lower end of a vertical shaft, L, that is screw-threaded and passes up through the beam C, having upon it a hand-wheel, M, above the beam and a similar wheel, N, beneath the beam. This latter disk is secured to the shaft in any ordinary way, and I have shown it connected by means of a neck, O, thereon fitting in a socket in the lower end of the shaft, where it is held by 45 transverse pins P', passing through the lower end of the shaft and through a groove, Q, in the neck of the disk. Between the lower end

of the shaft and the disk I prefer to place a washer, R, as shown in Figs. 1 and 4.

The lower hand-wheel of the shaft acts merely 55 as a jam-nut to hold the upper disk down upon the plate while the plate is being flanged, and by loosening upon this hand-wheel, the other hand-wheel may be turned to elevate this upper disk and release the plate between the two disks.

S represents T or I shaped sliding blocks or heads held between the plates composing the beam B. Their upper and lower ends overlap the plates, as shown in Figs. 1, 2, and 3, so that they are held from vertical movement, while they are free to be slid back and forth to suit plates of different sizes. They are moved back and forth by means of feed-screws T, working through boxes T', secured to the frame of the machine, and their inner ends are preferably connected to the heads by means of brackets T'', fitting over heads on the screws, as shown in Figs. 1 and 3. It will thus be seen that by turning the screws 75 in either direction the heads are moved in or out, as desired. These heads carry the formers T', over which the plate is flanged.

The formers consist of pins U, having heads U', over which the plate is bent. I prefer to 80 recess the sliding blocks or head, as shown at V, Fig. 3, to form an oil-chamber for the purpose of lubricating the pins, and I also prefer to place between the heads of the formers and their sliding blocks or heads anti-friction balls 85 or rollers V', as shown in Fig. 3. When the plate to be flanged is put in place, its outer portion extends over these formers, as shown in Fig. 1, and the part of the plate that extends beyond the formers is turned down to 90 form the flange, as shown in Fig. 3, by means of rollers W, held in frames W', pivoted at W' to sliding blocks W'', the latter being supported on and guided by the beam-flanges, which they are constructed to straddle in rear 95 of the former-heads. The frames are provided with rack-segments W'', into which mesh worms W', having rods W'' and hand-wheels W''. The frames and rollers are arranged above the plates, and are adapted to 100 be turned down by means of these worms working between the teeth of the rack-segments, from the position shown in Fig. 1 to that shown in Figs. 2 and 3, and as they are

thus turned down they bend the plate, forming the flange thereon.

The blocks W^2 may be moved back and forth, to suit plates of different diameters or sizes, by means of screw-rod X, passing through the uprights of the frame and provided with hand-wheels X', their inner ends being connected to the blocks by means of screws X^2 , passing through the blocks and fitting in grooves in the heads of the rods, or by other simple means.

The blocks W^2 are so connected to the beam B of the frame that they straddle and slide freely back and forth thereon, and are held to an adjustment by the feed-screws X.

15 As a means for conveniently adjusting the plate centrally upon the disks, I graduate one or both of the plates comprising the beam B, as shown at B⁶ in Fig. 2, and before putting the plate in place move one of the sliding blocks W^2 to the number on the beam that corresponds to the number of inches of the diameter of the plate to be flanged, and then, when the plate is put in place, it is only necessary to move up the other sliding block W^2 20 until it comes against the plate to be flanged, as shown in Fig. 1.

As an additional support for the plate while it is being flanged, I provide upon one side of the beam B an extension, B', which supports 30 a roller, B², in a sliding block, B³, which may be adjusted in or out by a rod, B⁴, to suit plates of different diameters. The rod is provided with a hand-wheel, B⁵, by which it is turned.

The chambers V may be filled with oil 35 through means of perforations V², extending down vertically through the formers, as shown in Fig. 2 and by dotted lines in Fig. 3.

By using the sliding blocks W^2 to center a plate upon the blocks the ordinary centering-40 pin, which is on one of the disks and passes through a hole in the plate, is dispensed with.

I claim as my invention—

1. The means for supporting the plate, which consists of a lower beam, B, formed of two plates, uprights D, upper beam, C, central box, 45 E, secured between the plates of the lower beam, short spindle F, having head G at its upper end and cog-wheel G at its lower end, disk J, secured to the head, a vertical shaft screw-threaded at its upper portion, which 50 passes through the upper beam, disk K, secured to the lower end of the shaft, and hand-wheels M and N above and beneath the upper beam, respectively, substantially as set forth.

2. The combination, with means for supporting the plate, of the lower beam, B, formed of two plates, the sliding block S, held between the plates by its flanges, formed with recess V, former T², consisting of pin U and head U', having perforation V², and the feed-screw T, 60 having its head secured to the block, substantially as shown and described.

3. The combination, with means for supporting the plate, of the lower beam, B, formed of two plates, the sliding block S, supported between the plates, formed with a recess, former T³, consisting of a pin, U, and head U', and the feed-screw T, having its head secured to the block, substantially as set forth.

4. The combination, with means for supporting the plate, and a beam, B, formed of plates, of the additional support, B', consisting of an extension having a sliding block, B³, a roller, B², supported in the block, rod B⁴, and hand-wheel B⁵, substantially as shown and described. 75

JOHN O'BRIEN.

In presence of—

A. A. PAXSON,
CHARLES PICKLES.
